UNITED STATES PATENT OFFICE

HENRY L. SULZBACH, OF SIOUX CITY, IOWA

LAWN EDGER

Application filed October 21, 1927. Serial No. 227,703.

My invention relates to that class of horticultural implements which are termed "lawn edgers", and has for its object, primarily, to simplify the construction of, and to improve the operation of, such instruments. These devices have heretofore been patterned after plows used for turning earth in fields and have been cumbersome and difficult to operate. Most of these devices include a longitudinal beam or shaft, a pair of wheels or pairs of wheels to support said shaft and a cutting blade or share supported between the wheels or rearwardly thereof and depending from the shaft proper. In many instances, discs have been employed for piercing the sod. These devices have been cumbersome for the reason that the shares have not been positioned to receive the full power applied to the shaft by the operator.

My invention contemplates a substantially straight shaft provided at one end with a handle which may be grasped by both hands of the operator so as to enable him to manipulate the implement with comparative ease, a pair of wheels supporting the other end of the shaft and a share or digging blade secured to the forward end of the shaft and projecting forwardly therefrom in substantial alignment therewith so that pressure exerted against the handle may be transmitted directly in a line with the shaft to the share, the wheels serving as a fulcrum, about which the share may be manipulated by movement of the shaft at its other end.

A further object of the invention is to provide a simple and substantial share construction having integral means for securing it to the shaft and so shaped as to avoid clogging of earth between the share and the end of the shaft directly therebehind.

Another object of the invention is to provide means for adjustably clamping the wheel axle to the shaft.

With these and other objects in view, my invention consists in the construction, arrangement and combination of the various parts of my device, whereby the objects contemplated are attained, as hereinafter more fully set forth, pointed out in my claims, and

illustrated in the accompanying drawings, in which:

Fig. 1 is a plan view of the implement.

Fig. 2 is a sectional view taken on the line 2—2 of Fig. 1.

Fig. 3 is an enlarged, detail, sectional view taken on the line 3—3 of Fig. 2.

Fig. 4 is a detail, sectional view taken on the line 4—4 of Fig. 2.

I have used the reference character 10 to indicate the shaft of the implement which is preferably made of wood but which may also be constructed of metal, such as, for instance, a channel arm or tubular construction. At one end, a double handle 12 is secured to the shaft in a transverse position so as to enable the operator to obtain a very secure grasp for manipulation of the implement.

An axle 13 is extended through an opening 14 provided for it in the shaft 10 and is clamped in position by means of a yoke 15 having the side arms 16 provided with notches 17 adapted to receive the axle 13. Connecting elements are used for adjustably securing the yoke 16 to the shaft 10 and preferably assuming the form of bolts 18 extending through registering openings in the yoke 16 and the shaft 10 and secured by nuts 19 threaded into the bolts 18 and engaging the shaft so as to draw the yoke toward the shaft. Thus it will be seen the yoke may be tightened so as to exert pressure against the axle 13, which in turn is securely clamped against one side of the opening 14. Thus the shaft may be secured in place in any of several longitudinally adjusted positions.

Wheels 20 are journaled at the ends of the axle 13.

A share, which is referred to generally by the reference character A, is formed of a heavy plate of steel having a generally triangular shaped blade 21 provided with a cutting edge 22 and an opposed, substantially vertical, share 23. The blade 21 and share 23 are formed by bending up one side of the triangular shaped blade, thus forming a generally trough-shaped share, the share being positioned substantially vertically and the blade being inclined from the lower ex-

100

tremity of the share upwardly and outwardly substantially at the angles shown in Fig. 3. A dividing shoulder 24 is thus formed between the share and blade and this dividing shoulder is positioned in a vertical plane, which is substantially co-axial with the shaft 10, as indicated in Fig. 1.

Formed integrally with the share is a bracket 25, which is shaped to embrace the shaft 10 and provided with a pair of openings for reception of bolts 26 extended through the shaft and through the bracket for securing the latter to the shaft.

A neck 27, which is considerably reduced, connects the blade 21 with the bracket 25 and is twisted so as to bring the blade to a proper angle relative to the shaft. It may now be noted that the lower portion of the blade 21 and the share 23 are both cut away so as to form this reduced neck and sufficiently to leave a space as at 28 between the rear extremity of the share and blade and the forward extremity of the shaft.

The vertical angle of the blade and share is such that the shoulder 24 is inclined relative to the shaft 10 at a substantial angle extending forwardly and upwardly from the shaft. The rear extremity of the shoulder 24 is below the longitudinal plane of the lower side of the shaft or substantially therein as shown in Fig. 2.

The implement is ordinarily used by placing the wheel at the left side of the device upon the sidewalk 29 and allowing the right wheel to travel upon the lawn. As the handle of the implement is swung to the right, the device will pivot about a vertical axis, intersecting the axle 13 and the share will swing to the left. Thus the implement may be manipulated so as to bring the share 23 as near to the edge of the sidewalk 29 as is desired and since the share projects forwardly beyond the shaft, the operator may very clearly see the exact position of the share relative to the sidewalk. I find that lateral adjustment of the share is rendered easy by virtue of the fact that the share is positioned at the forward end of the shaft. The lateral adjustment of the share thus is accomplished in the most natural manner, namely, by swinging a lever about a fulcrum, the handle of the lever being positioned at one end and the operating portion of the lever being at the other.

The same may be said of vertical adjustment of the share. By depressing the handle, the share is lifted, the axle again acting as the fulcrum. At this point, a difference may be noted between the operation of the implement of my invention as compared with those devices wherein the share is positioned rearwardly of the wheels. The pressure of the earth against the share as the latter tends to dig its way under the sod will have a tendency to lift the handle of my device, which

may be counter-acted by the weight of the arms of the operator pressing down against the handle, whereas in the other type of implement, the handles must be lifted upon in order to counter-act the digging tendency. Obviously it is more awkward and laborious a feat to constantly exert upward pressure against the handle than it is to exert downward pressure. For this reason the operation of the device is very substantially improved.

Another difference that may be here noted between the old type of implement mentioned and that of my invention resides in the fact that it is more difficult to clearly see the position of the share relative to the sidewalk when the share is positioned beneath the shaft. It is also more difficult to adjust the lateral position of the share.

Positioning the share forwardly of the shaft raises the problem of disposal of the earth which passes over the blade and this is solved by providing a space 28, hereinbefore described. It will be noted that the neck 27 is inclined outwardly and forwardly away from the end of the shaft, as indicated at 30 in Fig. 1. Thus the neck will serve to deflect the outer extremity of the strip of earth or sod which is being removed toward the opening 28 and the earth will then pass beneath the end of the shaft through this opening. The share 23 serves not only as a longitudinal guide but also to form the inner extremity of the cut. To this end it is sharpened at its upper edge as at 31.

It may now be noted that when the implement is inclined vertically at the usual angle indicated approximately in Fig. 2, that the cutting edge 22 will extend partially into the earth and partially above the earth. The same will be true of the cutting edge 31. A strip of earth will thus be smoothly sliced from the lawn, substantially triangular in cross section with its inner face vertical and its outer face inclined outwardly and upwardly away from the sidewalk. This strip of earth need not be very large since the object of edging is merely to prevent the grass which cannot be reached by a lawn mower from growing higher than the rest of the lawn.

The width of the strip of earth which is removed may be regulated by the depressing or elevating the share. As the share is lowered into the earth, the width of cut will be increased. A normal cut is indicated in Fig. 2 where the line 32 is used to indicate the surface of the lawn.

In addition to the improvement in operation, effected by positioning the share at the forward end of the shaft and positioning the wheels near the share for obtaining a fulcrum the construction of my invention is considerably simplified and cheapened over previous structures. No supporting brackets are required for the share other than the in-

tegral bracket construction which may be formed at the same time that the share is formed.

Some changes may be made in the construction and arrangement of the parts of my invention without departing from the real spirit and purpose of my invention, and it is my intention to cover by my claims, any modified forms of structure or use of mechanical equivalents, which may be reasonably included within their scope.

I claim as my invention:

1. A lawn edger comprising a shaft of substantial thickness, a pair of wheels supporting said shaft intermediate its ends, a share and bracket formed integrally of a single piece of plate metal cut away intermediate its ends to form a reduced neck, the share being formed trough shaped with one side forming a blade and the other side a vertical knife, the blade being connected with the bracket by means of said reduced neck and the bracket being secured to one side of the shaft at one end thereof, the share projecting beyond the end of the shaft, the neck being positioned out of line with the shaft and the cutaway opening of the share allowing earth to pass under the end of the shaft, the wheels being adapted to support the shaft in an inclined position when the share is projected below the level of the wheels.

2. A lawn edger comprising a shaft of substantial thickness, wheels supporting said shaft, a share and bracket formed integrally of a single piece of plate metal, the share comprising a blade and a vertical knife, the blade being inclined upwardly and away from the knife and the latter and the adjacent portion of the blade being cut away to form a reduced neck connecting the blade with the bracket, said neck being twisted to position the bracket in a vertical plane, the bracket being secured to one side of the shaft at the end thereof, the share projecting beyond the end of the shaft, the neck being positioned out of line with the shaft, the cutaway opening of the share allowing earth to pass under the end of the shaft and the wheels being adapted to support the shaft in an inclined position when the share is below the level of the wheels.

Signed this 19th day of October, 1927, in the county of Woodbury and State of Iowa.

HENRY L. SULZBACH.
